Primary Examiner — Michael A Pratt(74) Attorney, Agent, or Firm — McDonald Hopkins LLC(57) CLAIM

The ornamental design for a mounting device for under bed hitch mounting system, as shown and described.

DESCRIPTION

FIG. 1 is a top, side perspective view of a mounting device for under bed hitch mounting system showing our new design;

FIG. 2 is a bottom, side perspective view thereof;

FIG. 3 is a top view thereof;

FIG. 4 is a bottom view thereof;

FIG. 5 is a side view thereof; and,

FIG. 6 is a side view thereof.

The broken lines in the Figures are for illustrative purposes only and form no part of the claimed invention.
